Inventor:

UNITED STATES PATENT OFFICE.

CHARLES W. LEE BARBER, OF COLORADO SPRINGS, COLORADO.

SKIRT-ELEVATOR.

SPECIFICATION forming part of Letters Patent No. 709,459, dated September 23, 1902.

Application filed May 1, 1901. Serial No. 58,359. (No model.)

To all whom it may concern:

Be it known that I, CHARLES W. LEE BARBER, a citizen of Great Britain, residing in the city of Colorado Springs, El Paso county, Colorado, have invented a certain new and useful Skirt-Elevator and Skirt-Supporter, of which the following is a specification.

My invention relates to improvements in skirt-elevating and skirt-supporting devices in which a wire frame is rigidly attached to a belt worn around the waist under the skirt and on which frame another wire frame is hinged, so as to hang down or be raised up, elevating the skirt as it is raised, and provided with lugs that latch it up when raised, so as to hold the skirt up until released by the wearer, as may be desired in walking on the street or in dancing, &c. I attain these objects by the appliance and mechanism illustrated in the accompanying drawings, in which—

Figure 1 is a vertical rear view of the entire device as it appears with skirt removed and showing parts of the belt broken away. Fig. 2 is a vertical side view of the skirt-elevator, showing tilting frame B locked up and supporting the skirt D; Fig. 3, a vertical side view of the skirt-elevator as worn by a lady with a side of skirt broken away to show skirt-elevator; Fig. 4, a vertical side view of skirt-elevator partly raised, showing the adjustable tapes a a a attached to skirt D.

Similar letters refer to similar parts throughout the several views.

The belt is of cloth or other suitable material. The two frames A and B with tapes a a constitute the entire skirt elevator and supporter. Base-frame A is made of wire and provided with eyes d d d, to which are attached tapes a a a, (tapes to be attached to the several eyes d d d, which may be increased or diminished to many or few in number, as desired,) so that they may be sewed or pinned to the inside of the skirt to hold it from slipping upward and downward as the tilting frame is elevated, and with square eyes b b, so as to allow a permanent surface with which to fasten it to belt C. B is the tilting frame, hinged to A by loops of the wire e e and provided with wards or lugs f f, made to engage and lock onto arms g g when the frame B is raised to a vertical position, and also provided with spring-eyes h h and projections i i.

It is plain that if tilting frame B is raised from its position in Fig. 1 to its position in Fig. 2 it will raise the skirt D twice the distance between o and m, and as it is being raised the projections f f are compressed toward each other by the spring and recoil of k k, h h, and m against g g, till bracket-catches p p engage g g, and thus prevent tilting frame B from dropping down or being pulled down by the weight of the skirt until it is released by compressing toward each other projections i i, thus releasing bracket-catches p p from arms g g and allowing tilting frame B to drop to its original hanging position and also allowing the skirt to hang down as formerly. It is plain that by shortening tapes a a, and thus confining skirt D closer to bar n, the skirt may be forced to rise higher than if the tapes a a were made longer and allowed the skirt D to move farther from bar n.

Projections i i are intended to be useful to enable the wearer to reach back and compress them from without and through the skirt, and thus releasing the tilting frame B from bracket-catches p p and arms g g, so that the skirt D may drop down to its normal position.

What I claim as my invention, and desire to secure by Letters Patent, is—

1. A skirt elevator and supporter frame, comprising a cross-bar n, having a bar g at each end projecting at right angles thereto and having eyes b, for attaching to a belt, tapes a secured to a bar n, a frame B movably connected to the bar n, and having brackets f, to engage the arms g, substantially as shown and described.

2. In an improved skirt elevator and supporter, the combination with wire frame B, movably attached to bar n, of frame A, and hinged thereon, provided with spring-eyes h, connected by bar m, arms k, carrying bracket-catches p, so made as to engage arms g, of frame A, having bar n, provided with eyes d, to which are attached adjusting-tapes a, substantially as described and for the purposes set forth.

CHARLES W. LEE BARBER.
